SULFAPYRIDINE-1-OXIDES

John V. Scudi, West Orange, Scott J. Childress, Newark, and David B. Reisner, Cedar Grove, N.J., assignors to Wallace & Tiernan Incorporated, Essex, N.J., a corporation of Delaware

No Drawing. Application April 18, 1957
Serial No. 653,516

5 Claims. (Cl. 260—239.8)

This invention relates to sulfapyridine-1-oxides and more particularly to new derivatives of sulfapyridine, which are more soluble in water and less toxic than many previously known sulfapyridine compounds. These new derivatives of sulfapyridine, according to the present invention, may be termed N-oxides or 1-oxides and have the following general formula:

In the formula above, up to two of the substituents R¹, R², R³ and R⁴ may be lower alkyl groups, i.e. there may be no such lower alkyl groups or one or two such groups, the remainder of these substituents in each instance being hydrogen. The present invention further includes compounds which are the N⁴-acetylated derivatives of the compounds above referred to and which have the general formula:

It is also contemplated that the invention shall include the alkali metal salts of any of the compounds represented by the formulae above referred to, i.e. in which the hydrogen atom, which is attached to the N¹ or sulfonamide nitrogen, is replaced by an alkali metal, as sodium.

Many sulfonamide compounds have been prepared and tested as anti-bacterial agents, which is the general field of utility of the compounds of the present invention. Only a few of the known sulfonamide compounds have been found acceptable in clinical use due to the fact that many such compounds are objectionable due to either or both of the following: (a) low anti-bacterial activity or (b) such strong and undesirable side effects as to make the use of such compounds impracticable. Furthermore, most of the so-called "sulfa drugs" are characterized by relatively low solubility in water in the range of pH 5-7.

This low water solubility may be attributable to the fact that sulfapyridine-type compounds are weak acids. Most of the commonly used sulfa compounds have pK_a values in the range of about 6.5 to 10.5 (pK_a is a physical chemical constant used for comparing acids and indicates the pH at which the acid tested is one-half neutralized). Thus, for example, sulfathiazole has a pK_a of 7.1, while sulfanilamide has a pK_a of 10.4. Most of the sulfa drugs depend on salt formation for appreciable water-solubility and are not very soluble at the physiological pH levels, particularly in urine, which can have a pH as low as about 5. Only a few sulfa drugs such as sulfisoxazole and sul-

2

fathiadiazole have pK_a values below 6. Low solubility of such a drug in urine can lead to dangerous calculus formulation in the renal tubules which can even terminate in death.

- 5 In conducting research work with sulfa drugs in attempting to overcome some of the undesirable characteristics of previously known drugs as aforesaid, it was discovered that the 1-oxides of sulfapyridine, according to the present invention, have generally lower pK_a values, or
10 in other words, substantially greater acidity. While sulfapyridine itself has a pK_a of 8.43, sulfapyridine-1-oxide according to the present invention has a pK_a of 5.25; in other words, it is more than a thousand times as acidic as the most nearly corresponding, previously known sulfapyridine. Practically, this means that at physiological pH levels in the bloodstream, the sulfapyridine-1-oxide will exist largely as the sodium salt, which is much more soluble than is the free acid. Such salts are, therefore, to be considered within the purview of the present invention, whether they are formed by physiological action in the host or are formed by chemical action prior to administering the drug in question. In the present instance, however, it is noted that the free acid of the sulfapyridine-1-oxide has itself a high intrinsic solubility; for example, 25 when sulfapyridine is dissolved in water having a pH of 4 and a temperature of 37° C. (i.e. normal body temperature), it is soluble to the extent of 50 mg. percent (i.e. 50 mg. of the drug are soluble in 100 cc. of water); whereas as sulfapyridine-1-oxide is soluble under the same temperature and pH conditions to the extent of about 200 mg. percent. There is given below in tabular form a comparison between the solubility of sulfapyridine-1-oxide, sulfisoxazole and acetylsulfapyridine-1-oxide, the table illustrating the solubility of these three drugs at different pH 30 values. The reason for including acetylsulfapyridine-1-oxide is that this compound is believed to be a metabolic product resulting from the administration of sulfapyridine-1-oxide.

TABLE I
Solubility comparison at 37° C.

	4.1 213	5.1 420	5.6 1,310	6.4 6,900	pH. Solubility, mg. per- cent.
Sulfapyridine-1-oxide.....					
Sulfisoxazole.....	{ 4.4 25	5.0 50	5.5 125	6.0 340	pH. Solubility, mg. per- cent.
Acetylsulfapyridine-1-oxide.....	{ 4.2 87	5.1 345	5.5 844	-----	pH. Solubility, mg. per- cent.

Since, as aforesaid, urine may have a pH as low as about 5, the high solubility of the undissociated compound and its metabolic product, both in accordance with the present invention, are highly important.

It is known that an acid of the type herein disclosed with a pK_a of 5.25 will form alkali salts which have a neutral or nearly neutral reaction. Hence these highly soluble forms of the drug can be injected without causing an alkali necrosis of the tissues at the site of the injection; or in the case of an intravenous injection, the venous thrombosis characteristic of those sulfa drugs which form the more alkaline salts.

Not only is sulfapyridine known in the prior art, but also a substantial number of the lower alkyl-substituted sulfapyridines are known. In general, the compounds of the present invention are prepared by suitably oxidizing the sulfapyridines of the prior art or the substituted sulfapyridine compounds, respectively, for example by oxidizing the acetyl derivatives thereof respectively with hydrogen peroxide in 90% formic acid solution or with peracetic acid. In general, this oxidation occurs at the

pyridine ring nitrogen or at the sulfonamide nitrogen, giving rise to two products. The latter oxidation gives substituted hydroxamic acid-type compounds such as the N^4 -acetyl- N^1 -hydroxysulfapyridine having the formula:

Since these hydroxy compounds do not exhibit the higher acidity, which is characteristic of the sulfapyridine-1-oxides of the present invention, it is possible to separate the two oxidation products, for example by dissolution of the acetyl sulfapyridine-1-oxide in sodium bicarbonate solution. The acetyl group may then be removed by basic hydrolysis so as to yield the sulfapyridine-1-oxide. Further particulars as to the preparation of this compound and the corresponding alkyl substituted compounds will be set forth hereinafter in examples which follow.

The structure of the sulfapyridine-1-oxide has been confirmed by acid hydrolysis, yielding sulfanilic acid and 2-aminopyridine-1-oxide. The structure of the by-product (N^4 -acetyl- N^1 -hydroxysulfapyridine) has been similarly determined by acid hydrolysis, in this case yielding acetic acid, sulfanilic acid, and 2-hydroxylaminopyridine. The novel compounds, according to the present invention, may be prepared as particularly set out in the following examples:

EXAMPLE 1

A solution of 17.7 g. of N^4 -acetyl sulfapyridine in 115 g. of 90% formic acid was treated with 17.7 g. of 30% hydrogen peroxide and kept at room temperature for four days. After removing the solvent in vacuo on a waterbath, the residue was dissolved in 10% acetic acid and allowed to crystallize. The orange product was a mixture N^4 -acetyl- N^1 -hydroxysulfapyridine and N^4 -acetyl sulfapyridine-1-oxide and amounted to 12 g. It was not necessary to separate the products before hydrolysis. Ten grams of the mixture were heated under reflux in 100 ml. of 2 N sodium hydroxide for one hour. The 4 g. of orange solid obtained on acidification were crystallized to give white crystals, M.P. 188.5°-189.5° C. This material was sulfapyridine-1-oxide. It gave a brick-red color with ferric chloride. The Tollens test was negative.

EXAMPLE 2

Another method of preparation involved the separation of the mixture prepared by the method of Example 1 prior to hydrolysis of the N^4 -acetyl group. This separation was readily accomplished by treatment with sodium bicarbonate solution, the 1-oxide dissolving. The insoluble N^4 -acetyl- N^1 -hydroxysulfapyridine melted at 178° C. (with decomposition) after crystallization from 90% alcohol. Acidification of the bicarbonate solution resulted in N^4 -acetyl-sulfapyridine-1-oxide, which was crystallized from water and alcohol to give the pure product, M.P. 220°-221° C. with decomposition. Hydrolysis of the N-oxide with 2 N sodium hydroxide gave sulfapyridine-1-oxide in a yield of 50%.

EXAMPLE 3

Thirty grams of N^4 -acetyl- N^1 -hydroxysulfapyridine was suspended in 90 g. of acetic acid and 30 g. of 40% peracetic acid and kept at room temperature for 24 hours with occasional shaking. The compound slowly dissolved as the reaction took place. The solvent was distilled off under reduced pressure on a water-bath and the residue treated with 400 ml. of water and sufficient sodium bicarbonate to give an alkaline solution. After standing overnight, the insoluble material had crystallized and was filtered off. The products were then worked up as in Example 2 to give 14 g. of crude N^4 -acetyl- N^1 -hydroxysulfapyridine-1-oxide (M.P. 244° C.) and 9.5 g. of crude

N^4 -acetyl- N^1 -hydroxyl- N^6 -methylsulfapyridine (M.P. 168° C. with decomposition). This hydroxy compound was discarded as it does not have the desired antibacterial action for which the compounds of the present invention are particularly desired.

EXAMPLE 4

$6'$ -ethylsulfapyridine-1-oxide.—A solution of 140 g. of N^4 -acetyl- $6'$ -ethylsulfapyridine in 140 g. of 98% formic acid and 280 g. of acetic acid was treated with 140 g. of 40% peracetic acid and kept three days in a water bath at room temperature. The solvent was concentrated to about 50 ml. in vacuo. Water was added and crystallization induced. The crystals were found to be N^4 -acetyl- $6'$ -ethylsulfapyridine-1-oxide and were recrystallized from alcohol to give 48 g. of cream-colored product, M.P. 233°-234° C. (dec.). The original filtrate was neutralized with sodium bicarbonate and the precipitate obtained was crystallized from alcohol several times, giving 14 g. of white product, M.P. 160° C. (dec.). This was N^4 -acetyl- N^1 -hydroxy- $6'$ -ethylsulfapyridine.

Hydrolysis for two hours of 47 g. of N^4 -acetyl- $6'$ -ethylsulfapyridine-1-oxide in 470 ml. of refluxing 2 N sodium hydroxide followed by acidification afforded $6'$ -ethylsulfapyridine-1-oxide. Upon recrystallization from alcohol, there was obtained 31 g. of the desired compound, M.P. 153°-155° C.

EXAMPLE 5

$3'$ -methylsulfapyridine-1-oxide.—Twenty-four grams of N^4 -acetyl- $3'$ -methylsulfapyridine was heated in 72 g. of acetic acid and 24 g. of 40% peracetic acid at 65° C. for 24 hours. The solvent was removed in vacuo and the residue treated with sodium bicarbonate solution. After standing overnight, the mixture was filtered, the filtrate was acidified and concentrated to yield 2.4 g. of N^4 -acetyl- $3'$ -methylsulfapyridine-1-oxide. Recrystallized from 50% alcohol, this melted at 235°-237° C. (dec.). Upon hydrolysis of the acetyl group as in the other examples, there was obtained 0.6 g. of recrystallized $3'$ -methylsulfapyridine-1-oxide, M.P. 198° C. (dec.).

Although the bicarbonate-insoluble material from this oxidation showed a positive Tollens test, it consisted largely of unreacted starting material and N^4 -acetyl- N^1 -hydroxy- $3'$ -methylsulfapyridine was not isolated.

EXAMPLE 6

$4',6'$ -dimethylsulfapyridine-1-oxide.—A mixture of 30 g. of N^4 -acetyl- $4',6'$ -dimethylsulfapyridine, 90 g. of acetic acid and 30 g. of 40% peracetic acid was kept overnight at room temperature. Some crystals had formed in the mixture and these proved to be N^4 -acetyl- N^1 -hydroxy- $4',6'$ -dimethylsulfapyridine, 5 g., M.P. 181° C. (dec.) (from alcohol).

The solvent was removed in vacuo and the residue taken up in sodium bicarbonate solution and filtered. Acidification afforded 6 g. of N^4 -acetyl- $4',6'$ -dimethylsulfapyridine-1-oxide. After recrystallization from dilute alcohol the compound melted at 234°-236° C. (dec.).

Hydrolysis to $4',6'$ -dimethylsulfapyridine-1-oxide, M.P. 221.5°-222.5° C., was accomplished as described above.

There is listed below in Table II certain data as to the N^4 -acetyl sulfapyridine-1-oxides which are to be included in the present invention as above generally set forth, this table showing certain characteristics as determined for different substituted and non-substituted compounds according to the present invention. The first column in the table below, designated "R," indicates the substituent or substituents in the pyridine ring, it being understood that the nitrogen of the pyridine ring is of the 1-position in the general formula first given above and the numbering is counterclockwise in the usual manner. It is further to be understood that all substituents as R^1 , R^2 , R^3 and R^4 of the general formula above, which are not substituted by alkyl group, are represented by hydrogen in the compounds listed in Table II.

5
TABLE II

R	M.P., °C.	Formula	Nitrogen, percent	
			Calcd.	Found
H	220-221	C ₁₁ H ₁₁ O ₂ N ₂ S	13.68	13.65
3'-OH	234-236	C ₁₁ H ₁₁ O ₃ N ₂ S	13.08	12.89

While there is herein disclosed but a few of the possible equivalents which are intended to be embraced within the scope of this invention, others will suggest themselves to those skilled in the art from the foregoing particular disclosure. We do not wish to be limited, therefore, except by the scope of the appended claims, which are to be construed validly as broadly as the state of the prior art permits.

What is claimed is:

1. A sulfapyridine-1-oxide compound having the formula:

which is selected from the group (a) in which up to two 75

of the substituents R¹, R², R³ and R⁴ are lower alkyl groups and the remainder of said substituents are each hydrogen, and the alkali metal salts thereof, and (b) N⁴ acetylated derivatives of the compounds of group (a) above having the formula:

and the alkali metal salts thereof.

10

2. The compound, 6' - methylsulfapyridine-1-oxide, having the formula:

35

3. The compound, 6' - ethylsulfapyridine - 1-oxide, having the formula:

45

4. The compound, 4',6'-dimethylsulfapyridine-1-oxide, having the formula:

50

55

5. The compound, 4' - methylsulfapyridine - 1-oxide, having the formula:

60

70
